AUTOMATIC FIRE ALARM RELAY

Milfred King Thomas, Birmingham, Ala.

Application December 7, 1951, Serial No. 260,363

1 Claim. (Cl. 200—87)

1 This invention relates to improvements in fire alarm systems, and more particularly to an improved automatic fire alarm system operated in response to the presence of a fire in a building or other establishment equipped with the improved system.

A main object of the invention is to provide a novel and improved automatic fire alarm system which may be employed in conjunction with conventional fire alarm apparatus, the improved system being relatively easy to install, being simple in construction, and being reliable in operation.

A further object of the invention is to provide an improved automatic fire alarm system adapted for use with conventional fire alarm equipment, the improved system involving inexpensive components, being sturdy in construction, and being easy to maintain in operating condition.

Further objects and advantages of the invention will become apparent from the following description and claim, and from the accompanying drawings, wherein:

Figure 1 is a schematic view showing one form of improved fire alarm system according to the present invention installed in conjunction with a conventional fire alarm switch box;

Figure 2 is a wiring diagram of the system illustrated in Figure 1;

Figure 3 is an enlarged cross-sectional detail view taken on the line 3—3 of Figure 1;

Figure 4 is a perspective view illustrating a modification of the solenoid employed in a system according to the present invention installed on another conventional form of fire alarm switch box;

Figure 5 is an enlarged cross-sectional detail view taken on the line 5—5 of Figure 4;

Figure 6 is a front elevational view, partly broken away, of another conventional form of fire alarm switch box equipped with improved automatic switch-operating means in accordance with the present invention;

Figure 7 is an enlarged cross-sectional detail view taken on the line 7—7 of Figure 6;

Figure 8 is a schematic diagram showing a further modification of the automatic fire alarm system of the present invention.

Referring to the drawings, and more particularly to Figures 1, 2 and 3, 11 designates a conventional fire alarm switch box of the manually operated type, the switch box being provided with a push button switch 12 to which access is ordinarily obtained by breaking a panel of frangible material, such as glass, located in the front cover of the box immediately adjacent to the push but-

ton switch 12. The front cover of the box, designated at 13, is formed with an aperture 14 to which is secured a rectangular frame 15. As shown in Figure 1, the frame 15 may be hinged to the front wall 13 at 16, 16, so that said frame may be swung to open position at times, the frame being maintained closed by any suitable latch means 17. Designated at 18 is a panel of suitable frangible material, such as glass or the like, which is secured in the frame 15, said panel having a central bulged portion 19 located opposite the push button 12. Secured on the frame 15 is a solenoid 20 comprising a casing 21 containing an annular insulating core 22 on which is wound the coil 23. Designated at 24 is a movable plunger of magnetic material slidably mounted in the core 22, and designated at 25 is a movable rod of non-magnetic material, such as brass or the like, which is slidably positioned in the annular core 22 between the plunger 24 and the inner end aperture 26 of casing 21. As shown in Figure 3, the plunger 24 is arranged so that when the coil 23 is energized, said plunger will be moved inwardly by magnetic attraction and will drive rod 25 against the centrally bowed portion 19 of the frangible panel 18, causing said panel to be shattered and allowing the movable rod element 25 to strike against the push button switch 12. When the push button 12 is engaged, the associated fire alarm apparatus is energized in the conventional manner.

Designated at 27 are respective thermostatic switches which may be located in strategic portions of the building or other establishment being protected, the respective thermostatic switches 27 being connected in parallel between wires 28 and 29. Wire 29 is connected to one terminal of the coil 23 of the solenoid 20. Wire 28 is connected through one movable pole 30 of a double-pole, single-throw switch 31 to a line wire 32 leading to one terminal of a suitable source of current. The other line wire 33 is connected through the second movable pole 34 of the switch 31 to a wire 35 leading to the remaining terminal of coil 23. It will be readily apparent that when switch 31 is closed, the closure of any one of the thermostatic switches 27 will complete the energizing circuit for the core 23 of solenoid 20, causing the plunger 24 to be driven inwardly and causing the non-magnetic rod element 25 to be driven through the frangible panel 18 and to cause the switch 12 to be closed.

Referring now to Figures 4 and 5, the fire alarm box, designated at 11', may be of a type 55 wherein the alarm switch is closed by the ro-

tation of a shaft 12'. In accordance with the present invention, a solenoid 20' is mounted in the forward portion of the alarm box 11' with its axis in a horizontal position at right angles to the shaft 12'. As shown in Figure 4, the box 11' may be suitably recessed or otherwise modified to receive and support the solenoid 20'. The solenoid 20' comprises the annular insulating core 22' in which is slidably mounted the magnetic plunger 24' which has secured to its forward portion a rack element 25' formed with rack teeth meshingly engaging the teeth 26' of a gear 27' secured on the end of shaft 12'. The electrical circuit employed with the embodiment of the invention of Figures 4 and 5 is the same as in the case of Figures 1, 2 and 3, and when one of the thermostats of the system becomes closed, the solenoid 20' becomes energized and retracts the plunger 24' from its normal position, shown in Figure 5, causing the shaft 12' to be rotated and thereby causing the alarm switch associated with the box 11' to be closed.

In the form of the invention shown in Figures 6 and 7, the alarm box, designated at 36, is of the type having the downwardly movable, horizontally projecting handle element 37 which is arranged to close the alarm switch, designated at 38, responsive to downward movement of the handle 37 from its normal position. In accordance with the present invention, the handle 37 is provided with an axial bore 39 which receives the laterally projecting end 40 of the solenoid plunger 41. The plunger 41 is slidably received in the axial bore of the annular insulating member 42 forming part of the solenoid 43, said solenoid being mounted on the wall 44 of the box adjacent the handle 37 in a vertical position. The energizing circuit for the solenoid 43 is the same as in the two preceding embodiments of the invention, and when one of the thermostats of the system closes, the solenoid 43 becomes energized, causing the plunger 41 to be pulled downwardly, whereby the handle 37 is moved downwardly to close the alarm switch 38 and to energize the associated alarm circuits.

In the embodiment shown in Figure 8, a means is provided for energizing the solenoid independently of the thermostats, if so desired. In Figure 8, the current supply wires are shown at 35' and 29', and the solenoid is shown at 40'. Designated at 45 is a manually settable switch of a conventional type which may be set to a closed position, if so desired. The thermostats 27 are connected in parallel between the line wire 29' and a wire 28' which in turn is connected to one terminal of the solenoid 40' through the manually settable switch 45. The other terminal of the solenoid 40' is connected to the line wire 35'. Connected

between the first-mentioned terminal of the solenoid 40' and the line wire 29', by wires 46 and 47, is a normally open push-button switch 48. When switch 48 is closed, the solenoid 40' is connected directly to the line wires 29' and 35', causing the solenoid 40' to be energized, and causing the alarm circuits to be activated. The switch 48 therefore corresponds to the usual fire alarm switch employed in alarm boxes. The manually settable switch 45 may be employed to set the alarm circuit for automatic operation by the closure of any one of the thermostats 27, as in the previously-described embodiments of the invention.

While certain specific embodiments of an improved fire alarm system have been disclosed in the foregoing description, it will be understood that various modifications within the spirit of the invention may occur to those skilled in the art. Therefore, it is intended that no limitations be placed on the invention except as defined by the scope of the appended claim.

What is claimed is:

25 In a fire alarm system, an alarm box having a vertical wall, a downwardly movable, horizontally extending manual alarm handle element mounted on said wall and projecting externally thereof, said handle element having an elevated normal position, an alarm switch in the box adjacent said wall, means secured to said handle element and engaging said alarm switch, arranged to close the switch responsive to downward vertical movement of the handle element from said normal position, said handle element being formed with an axial bore, a vertical plunger rod of magnetic material having a horizontal arm at its top end slidably engaged in said bore, whereby said vertical plunger rod is detachably connected at the upper end thereof to said handle element, and a vertical solenoid mounted in said fire box and slidably receiving said plunger rod axially therein, said solenoid being arranged to move the plunger rod downwardly responsive to energization of said solenoid, whereby to close said alarm switch.
